VALVE ASSEMBLY

Albert Feucht, Garfield Heights, Ohio, assignor to
The Cleveland Rock Drill Company, Cleveland,
Ohio, a corporation of Ohio

Application May 26, 1938, Serial No. 210,135

1 Claim. (Cl. 251—103)

This invention relates broadly to fluid actuated rock drills of the percussive type, but more particularly to a valve assembly for controlling admission of the motive fluid into the rock drill and supply of water to the drill steel.

One object of this invention is the production of a single valve member for controlling admission of motive fluid into the rock drill and supply of water to the drill steel, the supply of water being substantially concurrent with the admission of motive fluid, thereby preventing the formation of dust resulting from dry drilling.

Another object of this invention is the production in a rock drill of a motive fluid and water supply controlling valve member, the water controlling valve portion being preferably made of non-corrosive material cooperating with adequate packings for preventing water from contacting other movable parts of the rock drill.

Other objects and advantages more or less ancillary to the foregoing reside in the specific construction and aggroupment of the element peculiar to this structure, as will become apparent from a more complete examination of this specification.

In the drawing:

Fig. 1 is a cross sectional view of the back head of a rock drill embodying the invention.

Fig. 2 is a longitudinal sectional view taken in a plane indicated by line 2—2 in Fig. 1.

Fig. 3 is also a longitudinal sectional view taken in a plane indicated by line 3—3 in Fig. 1, showing the upper end of a rock drill.

Fig. 4 is a view similar to Fig. 2 showing the valve in another position.

Fig. 5 is a view similar to Fig. 1, showing a modification of the invention.

Referring to the drawing, 10 represents the cylinder of a rock drill having reciprocable therein a piston 11. Within the upper end of the cylinder, there is a suitable valve mechanism 12 through which motive fluid is distributed into the ends of the cylinder 10 for actuating the piston 11, motive fluid being supplied to the valve mechanism 12 from the annular groove 13 of a bearing plate 14 through passages 15. Interposed between the valve mechanism 12 and the plate 14, there is the conventional rotation mechanism including a rifle bar 16 projecting into the piston 11.

Secured to the cylinder 10 by bolts 17, there is a back head 18 formed with a central bore 19 which is threaded to receive a plug 20 by which the conventional water tube 21 is held in position.

This water tube extends through the machine

into the shank of the drill steel (not shown), and is formed with a head 22 supported by a resilient washer 23. Surrounding this washer, the head is formed with an annular groove 24, which is in constant communication with the interior of the tube 21 through ports 25 and 26 provided within the plug 20.

Extending transversally through the head 18, there is a bore 27 having the right end thereof in Fig. 1 enlarged and threaded to receive a plug nut 28 by which a hollow goose neck 29 is rotatably secured to the head for admitting motive fluid into the bore 27. The other end portion of the bore 27 is enlarged to form a counterbore 30 having pressed within the bottom portion thereof a bushing 31 preferably made of non-corrosive material such as brass or stainless steel. Rotatable within the bore 27, there

is a valve member 32 having a central bore 33 in communication with the goose neck 29, and a radial port 34 through which motive fluid may be admitted into the annular groove 13 of the bearing plate 14 through a passage 34'. The valve 32 is provided with an integral shank 35 extending through the bushing 31 and reduced in diameter to form an annular shoulder 36.

Mounted on the shank 35, there is a short sleeve 37 and a ferrule 38. The sleeve 37, which is also made of non-corrosive material, is secured on the shank 35 by a key 39 for rotation within the bushing 31, while the ferrule 38 is attached to the shank 35 by a screw threaded connection 40 through which limited axial movement

of the throttle valve relative to the ferrule is possible as explained hereinafter. The ferrule 38 is also formed with an external flange 41, one side of which engages the bushing 31, while the other side is engaged by a retaining nut 42 screwed within the bore 27. Screwed on the exterior end of the shank 35 and acting as a check

nut for the ferrule 38, there is a handle 43 through which the valve 32 may be rotated. The innermost end of the sleeve 37 and the shoulder 36 are tapered outwardly to receive therebetween an annular V-shaped packing ring 44, while the other end of the sleeve and the adjacent end of the ferrule 38 are similarly tapered to accommodate therebetween an annular V-shaped packing ring 45, which packing rings are made of compressible material engageable with the inner

wall of the bushing 31 and adjustably compressible between the annular shoulder 36 and the inner end of the ferrule 38 through the screw threaded connection 40. In practice, the sleeve 37 is closely fitted within the bushing 31, and

the shoulder 36 is tapered to receive the sleeve 37 therebetween. The sleeve 37 is secured to the shank 35 by the key 39, and the shoulder 36 is secured to the shank 35 by the retaining nut 42.

The shoulder 36 is tapered to receive the sleeve 37 therebetween. The sleeve 37 is secured to the shank 35 by the key 39, and the shoulder 36 is secured to the shank 35 by the retaining nut 42.

The shoulder 36 is tapered to receive the sleeve 37 therebetween. The sleeve 37 is secured to the shank 35 by the key 39, and the shoulder 36 is secured to the shank 35 by the retaining nut 42.

The shoulder 36 is tapered to receive the sleeve 37 therebetween. The sleeve 37 is secured to the shank 35 by the key 39, and the shoulder 36 is secured to the shank 35 by the retaining nut 42.

The shoulder 36 is tapered to receive the sleeve 37 therebetween. The sleeve 37 is secured to the shank 35 by the key 39, and the shoulder 36 is secured to the shank 35 by the retaining nut 42.

has its peripheral wall provided with a partly circular groove 46, which groove may afford communication between two passages 47 and 48 formed within the head 18. The passage 47 leads from the interior of the bushing 31 between the packing rings 44 and 45 to a threaded bore 49, while the passage 48 also leads from the interior of the bushing 31 below the passage 47, into the annular groove 24.

10 In the modification shown in Fig. 5, the valve member 132 is somewhat longer than the one shown in Fig. 1, and is rotatable within a bore 127 similar to the bore 21 above referred to, which bore is also enlarged to form a counterbore 130 having secured therein by a key 139, a bushing 131. The valve 132 extends through this bushing with which it is closely fitted, and is also provided with a reduced shank 135 forming an annular shoulder 136, which is engaged by a retaining nut 142 screwed within the bore 127 and held against accidental rotation by a check nut 50. The bottom of the counterbore 130 within which the bushing 131 is located, and the adjacent ends of this bushing are tapered 25 inwardly to receive therebetween an annular V-shaped packing ring 144, while a similar packing ring 145 is located between the other end wall of the bushing 131 and the adjacent end wall of the nut 142, which end walls are also tapered inwardly. In this modified construction, the throttle valve 132 and bushing 131 are preferably made of non-corrosive material. The shank 135 of the valve 132 is formed with a tapered portion 51 adapted to receive a handle 43 secured in position by a nut 52. The bushing 131 which is equivalent to the bushing 31, has the two passages 47 and 48 leading therefrom in the manner above referred to in connection with the bushing 31.

40 In the operation of the device, motive fluid such as compressed air is admitted into the valve-bore 33 through the goose neck 29, while water is admitted into the bore 49 through any suitable conduit (not shown). With the valve 32 positioned as shown in Fig. 2, the motive fluid conveying port 34 is out of communication with the passages 34', and the water conveying passage 47 out of communication with the passage 48, thereby preventing admission of motive fluid and water into the machine. When the valve is positioned as shown in Fig. 4, the valve port 34 is in communication with the passage 34' for admitting motive fluid into the groove 13, from where it is distributed by the valve mechanism 12 into the cylinder 10 for actuating the piston 11. In this instance, the passage 47 is in communication with the passage 48 through the valve-groove 46, thereby allowing water from the bore 49 to flow into the annular groove 24 via the passage 47, the valve-groove 46 and the passage 48. From the annular groove 24, water will flow into the tube 21 via the ports 25 and 26 of the plug 20, and from the tube into the drill steel to the bottom of the drilled hole. The position of the valve-groove 46

relative to the passage 47, is calculated to cause intercommunication of the passages 47 and 48 somewhat prior to the communication of the valve-port 34 with the passage 34' as the valve 32 is rotated from the position shown in Fig. 2 to 5 the position in Fig. 4, thereby admitting water to the bit end of the drill steel somewhat prior to or at least concurrently with the operation of the rock drill.

Due to the packing rings 44 and 45 carried by 10 the valve for rotation therewith in fluid tight engagement with the inner wall of the bushing 31, water is prevented from contacting any portion of the valve other than the bushing 31 and the sleeve 37 which are made of non-corrosive material, thereby precluding the formation of rust or the like and assuring a free rotation of the valve.

The compression of the packing rings 44 and 45 may be adjusted by loosening the handle 43 20 and rotating the ferrule 38 relative to the valve-shank 35, thereby causing, due to the screw threaded connection 40, the axial movement of the valve-shoulder 36 toward or away from the inner end of the ferrule, which ferrule is free to 25 rotate but is maintained against axial movement by the nut 42 and the bushing 31 engaging the flange 41.

In the modification shown in Fig. 5, the packing rings 144 and 145 are stationary within the 30 counterbore 130 in fluid tight engagement with the valve 132. In this instance, the compression of the packings is adjustable by rotating the nut 142 after having first released the check nut 50, thereby causing axial movement of the nut toward or away from the bottom of the counterbore 131.

Although the foregoing description is necessarily of a detailed character, in order to completely set forth the invention, it is to be understood that the specific terminology is not intended to be restrictive or confining and it is to be further understood that various rearrangements of parts and modifications of structural detail may be resorted to without departing from the 45 scope or spirit of the invention as herein claimed.

I claim:

A valve assembly including a housing, a non-rotatable cylindrical bushing within said housing, a cylindrical valve member rotatable within said 50 housing extending through said bushing, water and motive fluid conveying passages within said housing the former leading through said bushing and the latter opening on said valve member beside said bushing, packing means on said valve 55 member between said passages, a sleeve within said bushing secured on said valve member for rotation therewith, said bushing and sleeve being made of non-corrosive material, and means on said sleeve and valve member for opening and 60 closing said passages upon rotation of said valve member.

ALBERT FEUCHT.
